UNITED STATES PATENT OFFICE.

LESTER W. MALLORY, OF JUNCTION CITY, OREGON.

VEHICLE.

Application filed December 14, 1921. Serial No. 522,356.

To all whom it may concern:

Be it known that I, LESTER W. MALLORY, a citizen of the United States, residing at Junction City, in the county of Lane and State of Oregon, have invented certain new and useful Improvements in Vehicles, of which the following is a specification, reference being had to the accompanying drawings.

10 This invention relates to certain improvements in vehicles and has relation more particularly to a device of this general character adapted to be employed by children and wherein the propulsion of the vehicle is manually accomplished, and it is an object of the invention to provide a novel and improved device of this general character in simulation of an aeroplane so that the attraction of the device to children is materially enhanced.

Another object of the invention is to provide a novel and improved device of this general character constructed in a manner wherein the body is wheel-supported, certain of said wheels having driving means associated therewith and adapted to be operated by the pedal extremities of a child, together with means whereby the body may be adjusted with respect to the driving means so that the device in its entirety may be adjusted as the requirements of practice may necessitate and particularly to accommodate children of different sizes.

An additional object of the invention is to provide a novel and improved device of this general character wherein all of the exterior or outside parts may be readily and conveniently removed and packed within the body, and which is of particular advantage for shipping or storing within a small space.

Furthermore, it is an object of the invention to provide a device of this general character having novel and improved means whereby the direction of its travel may be effectively controlled by the child occupying the seat of the vehicle and without interference to the manual operation or driving of the vehicle by said child.

It is also an object of the invention to pro-

vide a novel and improved device of this general character including a body provided with a seat structure, said structure being located in a position whereby the possibility of the vehicle accidentally tipping or turning over is substantially eliminated.

The invention consists in the details of construction and in the combination and arrangement of the several parts of my improved vehicle whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in side elevation of a vehicle constructed in accordance with an embodiment of my invention;

Figure 2 is a view in top plan of the device as herein disclosed, certain of the parts being indicated by dotted lines;

Figure 3 is a longitudinal sectional view taken through the device as illustrated in Figure 1, with certain of the parts in elevation;

Figure 4 is a view in front elevation of the device as herein disclosed;

Figure 5 is a fragmentary view in detail illustrating a mounting of one of the ground engaging wheels;

Figure 6 is a fragmentary view illustrating in detail the mounting of a second ground engaging wheel and the mounting associated therewith; and

Figure 7 is a cross sectional view taken through the axle and sleeve disclosed in Figure 6, the coacting parts being in elevation.

As disclosed in the accompanying drawings, B denotes an elongated body, preferably hollow, and which closely simulates the fuselage of an aeroplane. The sides 1 of the body B may be of wood or other material and are bent in the manner disclosed in the accompanying drawings, with the rear end

portions of said sides 1 converging and secured together, as at 2. The forward portions of the side members 1 are secured to the member 3 in simulation of a radiator 5 having its upper edge curved. Secured to this upper curved edge of the member 3 and backward along the top edges of the sides 1 is a sheet 4, preferably of metal, and which simulates a hood, said sheet 4 extending back- 10 ward under the top plane P to be herein-after more particularly referred to.

Arranged between the two sides 1 of the body B a distance back of the planes P and P' far enough to make room for a child to 15 sit is a seat structure S. The top plane P in advance of the structure S is cut away, as at 5, to make further room for the child and to particularly facilitate entrance and exit.

The seat structure S has a back 6 disposed on a slight rearward incline with its upper edge rounded or curved. The upper or curved part of the back 6 extends above the sides 1 of the body B as does the radiator member 3. Secured to the upper rounded 25 edge of the seat back 6, the upper edges of the side members 1 rearwardly of the back and to a rounded member 7 is a sheet 8, preferably of metal. The mounting of this sheet 8 results in a rounded top, sloping to the rear 30 of the body B and whereby the simulation of aeroplane is further increased. The rounded member or block 7 is positioned between the side members 1 of the body B in front of and in close proximity to the tail 10.

Arranged between the rear portions of the side members 1 and supported thereby are the vertically spaced members 9 of suitable material, the upper member 9 being substantially flush with the top edges of the members 1. The tail 10 is horizontally disposed 40 and is held in applied position by screws or the like disposed through the tail and engaged with the upper member 9.

It is to be noted that the seat structure, or 45 more particularly the bottom thereof, is positioned adjacent the lower margins of the side members 1. This is of material advantage because, when the seat is occupied by a child, the possibility of the body B being 50 tipped or turned over is substantially eliminated.

To further enhance the appearance of the device in its entirety and especially in simulation of an aeroplane, the upper marginal 55 portions of the side members 1 are partially cut away, as at 11, said cut away portions being in advance of the seat back 6 and extending along what may be termed, in the present device, the cock-pit.

12 denotes a vertically disposed rudder post provided at its lower portion with a fork 14, the portion of the post above said fork being circular in cross section. The upper portion of the post 12 is disposed 60 through aligned openings in the members 9

and the tail 20 whereby the post is rotatably engaged with the body B. The post 12 extends above the rear portion of the body B and has secured thereto a rudder R which turns with the post so that during a steering 70 operation of the vehicle an effective imitation is given of the operation of an aeroplane. However, the rudder R, in fact, serves to facilitate or aid the steering of the body B to a small degree by the action of the air 75 upon the rudder R.

Rotatably supported within the fork 14 of the post 12 is a ground engaging wheel W, the same preferably having a rubber tire 80 or tread.

The top plane P extends across and above the body B and to opposite sides thereof and comprises a single piece of material, such as wood, metal, or the like, and is secured by the 85 screws 15 or other fastening members to the upper ends of the vertically disposed uprights 16. The uprights 16 are arranged in pairs at each side of the body B and are fastened by screws 17 or the like to the adjacent side member 1.

The lower planes P' extend outwardly from opposite sides of the body B and the inner end portion of each of said planes P' is secured by screws 18 or the like to the lower 95 ends of the uprights 16. Interposed between the outer end portions of the planes P and P' are uprights 19, the opposite end portions of said uprights being secured to the planes P and P' by the screws 20 or their 100 equivalents.

By having the upper plane P of a single piece, the construction of the device in its entirety is greatly strengthened and at the same time the construction of the device is 105 materially simplified with a resultant reduction in the cost of production.

A denotes the front supporting axle provided with the oppositely directed cranks 21. Fixed to one end portion of the axle A 110 is a ground engaging wheel 22 and loosely mounted upon the opposite end portion of the axle A is a second ground engaging wheel 23. By having the wheel 23 loose, the turning movement of the vehicle is materially facilitated and to better advantage than if both of the wheels 22 and 23 were 115 fixed to the axle A.

Loosely mounted upon each end portion of the axle A is a bearing or sleeve 24 having 120 a transverse groove 25 in its lower portion when applied and in which groove seats the bolt 26 intersecting the kerf 27 of the lower bifurcated end portion of an elongated member or rod 28. The sleeve or bearing 24 is arranged within the kerf 27 adjacent the inner end thereof when in applied position.

The member or rod 28 is disposed upwardly on a predetermined rearward incline and has its upper extremity bolted or otherwise secured, as at 29, to the side member 125

1 of the body B in close proximity to the front end of said body. Pivotally connected by a bolt 30 or the like with the lower end portion of the rod or member 28 is an end 5 portion of a rod or member 31. This member or rod 31 is also disposed upwardly and rearwardly on a predetermined incline and the upper end portion thereof is secured to the body B, or more particularly to a side 10 member 1 thereof, by a bolt 32. The bolt 32 is adapted to be disposed through one of the longitudinally spaced openings 33 in the body B or side member 1 thereof. By this means, the member or rod 28 may be raised 15 or lowered in accordance with the size of the child to use the device or as may otherwise be required and effectively held in such adjustment. By raising or lowering the members or rods 28, the reach from the seat 20 structure S to the cranks 21 will be lengthened or shortened as desired.

Loosely engaged with the cranks 21 are the pedals 34. By the use of these pedals, the feet of the child are kept from slipping 25 off of the cranks and the resultant friction during the driving of the vehicle is reduced and at the same time the wear on the shoes worn by the child is minimized.

35 denotes a vertically disposed steering 30 rod or joy stick depending from the upper plane P adjacent its rear marginal portion, said rod or stick being in swivel connection with the plane P through the instrumentality of the screw 36 loosely disposed through 35 the plane P and engaged with the upper end of the rod or stick. The rod or stick 35 adjacent its upper end and in relatively close proximity to the upper plane P is provided with the integrally formed and oppositely 40 directed arms 37 which are adapted to be engaged by the hands of the child occupying the seat structure S and whereby said child is permitted to have effective control of the direction of travel of the vehicle.

45 The rod or stick 35 is also freely disposed through a member 38 extending outwardly from the bottom of the seat structure S. The rod or stick 35 below the member 38 is provided with a cross head 39 in parallelism 50 with the arms 37. Wires 40 or the like are secured to the outer end portions of the cross head 39 and extend rearwardly in crossed relation and are secured to the oppositely directed eye-bolts 41 secured to the 55 rudder post 12. The wires 40 are crossed between the steering post or stick 35 and the rudder post 12 so that when the steering post or stick 35 is turned in one direction, the rudder post 12 will be caused to turn in 60 the opposite direction resulting in the turning movement of the forward end of the vehicle being in the same general direction in which the steering post or stick 35 has been turned.

65 It is to be understood that the lower por-

tion of the body B forwardly of the seat structure S is open whereby sufficient room is provided to permit the limbs of the child to have the requisite movement to rotate the axle A.

The lower portion 6' of the seat back 6 is removable. This is of advantage because it is possible that the exterior or outer parts of the device, when removed, may be readily packed within the body for shipping or to 75 permit the device, when not in use, to be stored in a small space.

Rotatably supported by the forward end of the body B, or more particularly the member 3, is the propeller Y whereby the 80 simulation of an aeroplane is further effected.

From the foregoing description it is thought to be obvious that a vehicle constructed in accordance with my invention is 85 particularly well adapted for use by reason of the convenience and facility with which it may be assembled and operated, and it will also be obvious that my invention is susceptible of some change and modification 90 without departing from the principles and spirit thereof and for this reason I do not wish to be understood as limiting myself to the precise arrangement and formation of the several parts herein shown in carrying 95 out my invention in practice except as hereinafter claimed.

I claim:

1. A vehicle of the class described comprising a body having a seat therein adjacent the bottom of the body, propelling means for the body, a plane disposed across and extending beyond opposite sides of the body, a steering rod depending from and in swivel connection with the plane, a member 100 extending outwardly from the seat, said steering rod being loosely disposed through said member, a steering post rotatably supported by one end portion of the body, a ground engaging member carried by the 105 post, a cross head carried by the lower portion of the steering rod, an operative connection between the cross head and the steering post whereby the steering post is turned upon rotating the steering rod, and means 110 carried by the steering rod below the plane for rotating the steering rod.

2. A vehicle of the class described comprising a hollow body provided with a seat, a bottom portion of the body forwardly of the seat being open, a wheel supported axle underlying said open portion of the bottom of the body, said axle, being provided with cranks adapted to be operated by the occupant of the seat, sleeves loosely mounted 120 upon the opposite end portions of the axle, each of said sleeves having a transversely disposed groove in its lower portion, members pivotally engaged with the opposite 125 sides of the forward portion of the body and 130

depending therefrom, the lower end portions of said members being bifurcated, each of the sleeves of the axle being received within the kerf of the bifurcated portion of each of said members, a shank carried by each of said members intersecting the kerf of the bifurcation thereof, said shank seating

within the groove of the sleeve, and a member pivotally engaged with each of the first named members and with the body. 10

In testimony whereof I hereunto affix my signature.

LESTER W. MALLORY.
